CIRCUIT CONTROLLING DEVICE

Joseph F. Ebert, Hollis, N. Y., assignor to Signal Engineering & Manufacturing Company, New York, N. Y., a corporation of Massachusetts

Application February 6, 1933, Serial No. 655,369

5 Claims. (Cl. 175—336)

The present invention relates to circuit controlling devices or relays, and has for its object to provide a relay in which the armature is adjustable for the purpose of controlling the current value at which the relay will operate.

The present invention contemplates the provision of a device, in the form of an attachment to a relay, which comprises a support having a gap determining member engaging the armature at a point removed from its pivot, said gap determining member being closely adjustable so as to permit very accurate setting of the current value at which the armature will pull up. In addition, the device provides an adjustable tension member connected to the armature and which establishes a predetermined pull on the armature away from the core of the relay, thereby providing for a further adjustment of the current value at which the armature will be actuated. Lastly, the device incorporates a latch which is adapted to engage automatically beneath the armature for locking the latter in the position which it occupies when the coil is energized, with provision of means by which the latch may be released.

Other and further objects and advantages of the invention will appear from the following description taken in connection with the accompanying drawing, in which:—

30 Fig. 1 is a front elevation of the lower portion of a relay showing the invention in connection therewith.

Fig. 2 is a side elevation as viewed from the left in Fig. 1, showing the upper portion of the 35 relay.

Fig. 3 is a side elevation of the device of Fig. 1, as viewed from the right.

Like reference characters refer to like parts in the different figures.

40 Referring to Fig. 2, the relay comprises a base 1, with an energizing coil 2 mounted on the front leg of a U-shaped core 3. An armature 4 is pivotally mounted at 5 on the lower end of the rear core leg and the end of said armature 45 extends beneath the end of the shorter core leg. The armature 4 carries a horizontal supporting member 6, Fig. 1, to the ends of which spring contact arms 7 are secured, and the upper ends of arms 7 are normally in a position in which 50 they are separated from spaced stationary contacts 8 mounted on the base 1. When the coil is energized, the armature 4 is swung upwardly, thereby moving the contact arms 7 from the inoperative position shown in Fig. 2 into engagement with said stationary contacts 8.

In accordance with one embodiment of the present invention, an attachment is secured to the lower end of the base 1 and carries the structure for adjustably supporting the armature. Referring to Fig. 2, the attachment comprises a bracket 11 having a horizontal portion 12 secured to the lower end of the base 1 by screws 13, the bracket extending downwardly and forwardly to provide a portion 14 on which the armature adjusting means is mounted. The outer end of the bracket is bent upwardly and provides at the upper end a horizontal portion 15 parallel to the horizontal portion 14. Said portions provide aligned vertical bores through which a rod 16 extends, the upper end of said rod being positioned to engage beneath the armature adjacent the free end thereof. The lower end of said rod carries a bearing portion 17, Fig. 1, engaging the periphery of a cam 18 eccentrically mounted on the inner end of an adjusting screw 20 carried in a depending portion 21 of the bracket, turning movement of the screw accordingly varying the position of the rod 16 to determine the air gap between the armature and the core of the coil. The head 22 of said adjusting screw is provided with knurling or grooves 23 parallel to the axis of said screw, and a spring finger 24 secured to the depending portion 21 of the bracket engages the grooves in said head to hold said screw 25 against turning movement when said screw is in adjusted position. A spring 25 secured to the portion 14 engages the bearing portion 17 of rod 16 to hold said rod in engagement with the cam 18. Thus, as the screw 20 is turned in the portion 21 of the bracket, the rod 16 is raised or lowered to vary the position at which said rod engages the armature, thereby supporting the armature in predetermined spaced relation to the end of the core of the coil.

45 A bracket 26 is secured by screws 27 to the base 1 in parallel relation to the bracket 11 and provides a horizontal portion 28 substantially in the plane of the portion 14 of the bracket 11. A depending portion 30 extends 100 from the portion 28 and supports a thumb screw 31, the head 32 of which is knurled to provide grooves 33 with which a spring finger 34 carried by the portion 30 engages for supporting said screw against turning movement. The thumb screw 31 has a cylindrical portion on the inner end thereof around which one end of a cord 35 is wrapped with the other end of said cord extending upwardly through an opening 35' in the portion 28 and connected to the lower end 105 of
